Primary Examiner—Wallace R. Burke*Assistant Examiner*—Robin V. Taylor*Attorney, Agent, or Firm*—Richard B. O'Planick; Lisa B. Riedesel[57] CLAIM

The ornamental design for a bucket, as shown and described.

DESCRIPTION

FIG. 1 is a top right rear perspective view of a bucket showing my new design. The broken lines are for illustrative purposes only and form no part of the claimed design;

FIG. 2 is a front elevational view thereof;

FIG. 3 is a rear elevational view thereof;

FIG. 4 is a right side elevational view thereof; the left side elevational view being a mirror image;

FIG. 5 is a top plan view thereof; and,

FIG. 6 is a bottom plan view thereof.

FIG. 1

FIG. 4
